RICHARD WALTER SCOTT, OF BECKENHAM, ENGLAND, ASSIGNOR TO S. GUITERMAN
AND COMPANY, LTD., OF LONDON, ENGLAND

TOY FIREARM

Application filed July 9, 1932, Serial No. 621,675, and in Great Britain July 20, 1931.

This invention relates to toy firearms of the type in which percussion caps are detonated by a hammer; and relates particularly to that type in which a band or strip of paper or like material having percussion caps regularly spaced thereon may be fed intermittently through the firearm, the caps then being detonated successively.

According to the invention a device is provided for feeding the cap strip or band through the firearm, with which the detonating hammer is actuated in correlated succession by means of a cam, the movement of which can be controlled from the exterior of the firearm.

The feed device is arranged frictionally to engage the upper surface of the cap strip at each operation, partly by pressure against the side of a cap and partly by frictional contact with the strip surface, and it feeds the strip through the firearm an amount equal to the cap spacing, thereby so locating the caps that each one will be detonated in turn by the hammer.

The operating surfaces of the cam are so arranged with respect to each other that during the operation of the cam, the hammer may if desired remain in its detonating position for a short period after a cap has been detonated, during which time the feed device is retracted by its associated cam to a position preparatory to initiating the feed of the next percussion cap. Due to the frictional engagement of the hammer on the cap strip, the feed device during retraction is enabled to pass over the upstanding cap which is next to be detonated, and thereby reach a more distant position, where it can again frictionally engage the strip and cap to move it into the desired position.

The cam is preferably of circular form having a peripheral cam surface and another surface perpendicular thereto. It may be mounted for rotation on a horizontal spindle which projects to the exterior of the firearm casing and has a handle or lever thereon by which it may be rotated. The cam surfaces produce an oscillating movement of the hammer and the feed mechanism and may conveniently be formed so that two feeding op-

erations and two detonations occur for each complete rotation of the cam spindle, although any desired number of these operations may be arranged to occur for each rotation of the cam.

The percussion hammer preferably comprises a lever disposed within the firearm casing and pivoted thereto about a horizontal axis. The hammer lever bears on the peripheral cam surface so as to follow the cam, and may be biased to the detonating position by a spring or other resilient means to increase the force of the blow.

The cap strip feed mechanism preferably comprises a lever pivoted at one end to the body of the firearm about an axis perpendicular to the axis of the hammer lever and suitably shaped at its other end to bear on the cap strip and feed the latter through the firearm. This feed lever follows the vertical cam surface and is resiliently maintained in contact therewith by means of a spring or similar device.

In some cases it may be found desirable to form the vertical cam surface with an inclined ramp with which a headed pin or the like on the feed lever cooperates so that a vertical movement is imparted to the feed lever in addition to the transverse horizontal movement. In this way the feed lever will be raised while it is being retracted and thus obviates frictional engagement of this lever with the cap strip during retraction.

With this construction it is sometimes unnecessary to arrange for the detonating hammer to remain in its detonating position during the reverse movement of the feed lever as hereinabove described.

A preferred embodiment of the invention is illustrated by way of example in the accompanying drawing, in which

Figure 1 is a side elevation of the embodiment,

Figure 2 is a longitudinal sectional view of the operating mechanism for the firearm,

Figure 3 is a sectional plan of the part shown in Figure 2,

Figures 4 and 5 show respectively in sectional side elevation and in plan a cam form-

ing part of the mechanism, Figure 4 being a section taken on the line 4—4 of Figure 5,

Figure 6 is a view of a detonating hammer, and

Figure 7 is a view of a feed lever.

Referring to the drawing, the firearm is constructed to represent a quick firing gun and comprises a barrel portion 1 fitting into a body 2 within which the detonating and feeding mechanism is disposed. The body portion is mounted on a base portion 3 by means of a universal joint 4 so that the firearm can be elevated or traversed through substantially wide angles, and a projecting arm 5 carrying a butt or handle 6 at the end is provided on the body for manipulating the firearm.

Within the body 2 is rotatably mounted a horizontal spindle 7 projecting to the exterior of the body and having mounted thereon a handle 8. On the inner end of the spindle is secured a cam 9 which is shown in detail in Figures 4 and 5. The cam 9 is provided with a peripheral cam surface 10 with which engages a projection 11 on a detonating hammer 12. The hammer is pivoted about a horizontal pin 13, and carries at its free end a detonating head 14 in which a vertical hole 15 is drilled to accommodate one end of a helical spring 16, which bears at its other end against the upper side of the body 2 to bias the hammer 12 in a downward direction.

The cam 9 is also provided with a vertical cam surface 17 against which is biased a pin 18 upstanding on a cap feeding lever 19. The lever 19 is pivoted about a pin 20 located in the lower side of the body 2 and is biased against the cam surface 17 by a helical spring 21, which bears at one end against a side of the body 2, and at the other end against an upstanding projection 22 provided on the feed lever 19. The upper end of the pin 18 carries a head 23 the lower side of which bears on an internal cam surface 24 on the cam 9. The free end of the lever 19 projects through a slot 25 in the rear end of the body 2 and is curved as shown at 26 to provide a finger grip. Slots 27 are provided in the sides 50 of the body 2 through which a cap strip may be passed, and a platform 31 is provided on which the strip lies. When introducing the strip into the firearm the lever 19 is lifted upwardly by means of the finger grip 26 so that the strip passes thereunder. When released, the lever 19 is biased due to its flexibility so as to bear on the surface of the cap strip.

The body portion 2 comprises a box-like member having one side 2a detachably clamped thereto by two bolts 28 and 29 passing therethrough and secured with nuts. The bolt 28 passes with substantial clearance through a hole 30 provided in the projection 65 22 of the lever 19, and through the center of

the helical spring 21, and the bolt 29 passes through the inner end of the barrel 1 and serves also to secure it in position within the body.

The surfaces 10, 17 and 24 of the cam 9 are arranged with respect to one another so that on rotation of the handle 8 in the direction of the arrow 32 the detonating hammer 12 is held in its upper position while the feeding lever 19 is allowed to move under the action of its biased spring 21 to follow the cam surface 17 and feed the cap strip through the body to locate a cap under the detonating hammer 12. On further rotation of the handle 8 the feed lever 19 remains stationary and the detonating hammer is allowed to strike the percussion cap. On still further rotation of the handle 8 the detonating hammer 12 is retained pressed by the spring 16 against the surface of the cap strip while the feed lever 19 is retracted in a substantially horizontal direction by the cam surface 17 and at the same time is slightly raised by the cam surface 24 cooperating with the head 23 on the pin 18 to lift the lever 19 over the next unfired percussion cap. Further rotation of the handle 8 causes the detonating hammer 12 to be lifted from the cap strip and also allows the lever 19 to frictionally engage the surface of the cap strip, and by a combination of frictional contact with the strip surfaces and pressure against the side of a cap, the cap strip is again fed through the body. This cycle of operations takes place twice for every complete revolution of the handle 8.

It will be obvious that the invention may be embodied in other types of toy firearms such as toy pistols, and that the construction, arrangement and operation of the firearm may be modified in many respects without departing from the scope of the invention.

For example the cam could conveniently be operated by a ratchet mechanism actuated by a trigger, or alternatively, it could be arranged to operate with a reciprocating motion. Various types of springs may obviously be employed in conjunction with the hammer lever and the feed lever.

Having now particularly described and ascertained the nature of my said invention and in what manner the same is to be performed, I declare that what I claim is:

1. A toy firearm of the type adapted to detonate percussion caps comprising a device for feeding a cap strip or band through said firearm, a hammer for detonating the caps, a manually operable cam, said device and said hammer being so disposed with respect to said cam as to be actuated thereby in correlated succession, the said cam being substantially circular, and being mounted about a horizontal axis, and having a peripheral cam surface against which the detonating hammer is biased, and a handle for rotating the said cam, the said feeding device comprising a lever

pivoted about an axis perpendicular to that of the cam and being biased against another surface of the cam, perpendicular to the said first mentioned cam surface.

- 5 2. A toy firearm of the type adapted to detonate percussion caps, comprising a body portion, a manually operable cam of substantially circular form, rotatable about a horizontal axis, a handle for rotating said cam, a lever
10 for feeding the cap strip or band through said body portion and pivoted about an axis perpendicular to the axis of the cam, said cam having a peripheral cam surface against which the said hammer is biased, said cam
15 also having a surface perpendicular to said first mentioned surface, and against which the said lever is biased, an upstanding member on said lever, and a substantially horizontal projection extending from said upstand-
20 ing portion, the said cam having an additional internal cam surface against which the said horizontal projection engages by its under side, whereby the said lever is raised slightly during its retraction movement, oc-
25 casioned by the said perpendicular cam sur-
face.

3. A toy firearm of the type adapted to detonate percussion caps comprising a device for feeding a cap strip or band through said fire-
30 arm, a hammer for detonating the caps, a manually operable cam, said device and said hammer being so disposed with respect to said cam as to be actuated thereby in corre-
35 lated succession, the said cam being substan-
tially circular, and being mounted about a horizontal axis, and having a peripheral cam surface against which the detonating hammer is biased and a handle for rotating the said cam, the said feeding device comprising a
40 lever pivoted about an axis perpendicular to that of the cam and being biased against another surface of the cam, perpendicular to the said first mentioned cam surface, the cam sur-
faces being so formed that two feeding opera-
45 tions and two detonations occur for each revo-
lution of the cam.

In testimony whereof I have signed my name to this specification.

RICHARD WALTER SCOTT. [L. S.]
